ORIENTING DEVICE

Harold J. Graham, Highland Park, and Paul F. Powder, Detroit, Mich., assignors to Graham Manufacturing Corporation, Detroit, Mich., a corporation of Michigan

Application February 17, 1950, Serial No. 144,728

9 Claims. (Cl. 193—43)

1

This invention relates to apparatus for axially orienting small pieces such as studs, rivets, pins or the like having portions with different diameters or cross sections so that they can be fed to an automatic welder or other automatic machine.

Objects of this invention are to provide a device which will successively orient a random assortment of small pieces so that the pieces have a similar axial arrangement, which operates rapidly and automatically, which can be adjusted to accommodate pieces of various lengths, which can be operated pneumatically, hydraulically or electrically, which has a minimum of moving parts, which is free from jamming, which lends itself to mass production techniques, which is simple in construction, which is economical to manufacture, and which advances the art generally.

In a principal aspect the invention contemplates two pairs of cooperating fingers disposed normally to each other at a distance substantially equal or slightly greater than the length of the shank or other portion of the piece having the greater diameter, which fingers can be arranged as tines of bifurcated members, opposing pins, or equivalent mechanical structure. The space between the fingers of the respective pairs is lesser than the diameter of the shank portion and greater than the diameter of the smaller or tip portion of the piece. Means are provided such as a plunger or finger which may be operated mechanically, electrically, hydraulically or pneumatically, depending upon the type of control system used upon the apparatus with which the orienting device is associated, successively to force between the pairs of finger studs supplied with random axial orientation of their tips. As a piece having its tip oriented in one direction is forced between the fingers, the shank portion is restrained by the fingers of one of the pairs as the tip portion thereof passes between the fingers of the second pair so that the piece is released without change in axial orientation. As pieces having their tips oriented in the opposite direction are forced between the finger pairs, the fingers of the second pair restrain the shank portion of each as the tip portion passes between the fingers of the first pair thereby turning the piece end for end so that all the pieces, regardless of their original arrangement, are released from the device with the same final orientation.

In a more specific aspect the device comprises a body having a cavity wherein studs are successively fed, for example, from a magazine. One

2

of the walls of the cavity is provided with a shoulder having associated therewith either a bifurcated lip or a pair of pins which shoulder forms a platform or recess wherein successive studs are brought to rest as they proceed through the cavity. A cooperating member has a bifurcated end or opposed pins normally arranged with respect to the lip at a distance from the bottom of a recess substantially equal to the length of the shank portion of the piece. The spaces between the tines (or opposed pins) of both the lip and the member are spaced at a distance greater than the diameter of the tip portion and lesser than the diameter of the shank portion so that as studs having random axial orientation are successively forced from the shoulder by the plunger means, the studs having their shank portion resting on the platform or recess are turned end for end, whereas the pieces having their tip resting on the platform or recess are pushed out directly so that all pieces are released from the device tip first.

In a further aspect the member having the bifurcated end is pivotally attached to the body at its other end. An eccentric contacts an intermediate point so that the distance between the bifurcated end and the bifurcated lip upon the shoulder can be varied thereby to adjust for studs having shank portions with different axial lengths.

These and other objects and aspects will be apparent from the following description of an illustrative specific embodiment of the invention referring to drawings in which

Fig. 1 is an elevation view of a first embodiment of the invention used to orient studs fed to a welding gun;

Fig. 2 is an end elevation view of the embodiment shown in Fig. 1;

Fig. 3 is a sectional view on line 3—3 of Fig. 2 with the operating plunger in the retracted position;

Fig. 4 is a sectional view on line 3—3 of Fig. 2 with the plunger in the extended position;

Fig. 5 is a fragmentary sectional view on line 5—5 of Fig. 4;

Fig. 6 is an enlarged fragmentary sectional view showing a stud with its shank end resting in the shoulder recess;

Fig. 7 is a fragmentary sectional view on line 7—7 of Fig. 6;

Fig. 8 is a fragmentary sectional view on line 8—8 of Fig. 6;

Fig. 9 is a fragmentary sectional view showing the manner in which the stud resting upon its

shank end is forced out of the shoulder recess by the plunger;

Fig. 10 is a fragmentary sectional view showing a stud with its tip end resting in the shoulder recess;

Fig. 11 is a fragmentary sectional view showing the manner in which the stud resting upon its tip end is forced out of the shoulder recess by the plunger;

Fig. 12 is a view similar to Fig. 10 of a second embodiment of the invention;

Fig. 13 is a view similar to Fig. 8 of the embodiment shown in Fig. 12; and

Fig. 14 is a view similar to Fig. 13 with the stud arranged oppositely.

The particular embodiment of the invention chosen for the purpose of illustration consists of a device 20 (Fig. 1) which axially orients studs S so that they are successively fed tip first through a tube 22 to the chuck of a welding gun 24 of the type, for example, similar to that shown in the copending application of Harold J. Graham, Serial No. 81,130, filed March 12, 1949, now Patent No. 2,610,278. The studs S are fed to the orienting device 20 through an escapement mechanism 26 and a tube 28 leading from a magazine 30 equipped with an electrically operated feeder for introducing the studs into the tube 28 whose conventional construction is not material to the present invention and hence need not be described.

As is shown in Figs. 2 and 3, the orienting device 20 comprises a composite body 32 having a back plate 34 to which are secured two intermediate plates 35 and 36 by means of the screws 38 which extend through aligned apertures in the intermediate plates and front plates 40 and 42 (Fig. 1) to engage corresponding threaded apertures in the back plate. Alignment of the various plates is maintained by dowel pins 44. An additional screw 46 projects through an aperture in the back plate 34 to engage a threaded aperture in the intermediate plate 36.

The remaining open portion of the front part of the device 20 is closed by a cover plate 48 which is pivotally secured by a large headed screw 50 so that it can be opened to allow access to the intermediate plates 35 and 36 and the mechanism carried thereby which is described in detail below. The front plates 40 and 42 and the cover plate 48 are preferably of a transparent synthetic acrylate resin so that the operation of the device can be observed by the operator.

The adjacent portions of the intermediate plates 35 and 36 are spaced to form an irregularly shaped cavity 52 whose front and rear sides are closed, respectively, by the back plate 34 and the cover plate 48, which cavity acts as a passageway for the studs. The feed portion 54 of the passageway is substantially square in cross-section, having a minimum dimension somewhat greater than the diameter of the shank portion of the studs to be oriented. At the bottom of the feed portion 54 is a shoulder having an insert 55 of an abrasive-resisting material such as tungsten carbide attached to the intermediate plate 35, for example, by silver soldering. As is best shown in Figs. 6 and 8, the insert 55 has a bifurcated lip 56 projecting normally upward thereby to form a cup or recess for receiving the forward ends of studs S dropped down the passageway 54.

A cooperating member 58 is pivotally connected at one end 59 to the back plate 34. The member 58 is disposed in a recess which normally

extends from the passageway 54 so that the tines of the opposite bifurcated end 60 are disposed adjacent the passageway 54 directly above the lip 56 of the insert 55. To prevent rapid wear 5 the bifurcated end 60 is preferably made of a separate piece of tungsten carbide which is silver soldered to the remainder of the lever 58. The distance between the bottom of the recess formed by the lip 56 and the bifurcated end 60 15 of the member 58 is determined by a screw 62 which is preferably provided with an eccentric head (Fig. 5) whereby the distance is adjusted to be equal substantially to the length of the shank portion of the stud S. The member 58 is yieldably urged against the screw 62 by a spring 64, one end of which bears against the member. The other end of the spring 64 is held by a screw 66 whereby the force exerted by the spring may be varied.

The cavity 52 is enlarged adjacent the insert 55 and the member 58 so that the stud resting in the recess of the insert can be moved laterally by means of a pneumatically operated finger or plunger 68. The tip 70 of the plunger 68 is made 25 of tungsten carbide or other abrasive-resisting material silver soldered or otherwise secured to the end of the plunger. The opposite end of the plunger 68 is pressed into an aperture in a skirted piston 72 which is reciprocatingly disposed in a cylinder block 74 secured to the back plate 34 by the cap screws 76. The plunger 68 is biased 30 in a retracted position by a spring 78, one end of which is seated in the recess formed by the skirt of the piston 72. The other end of the spring 78 engages a seat 80 which is pressed into both the body 32 and the block 74 thereby to maintain alignment of the cylinder and the aperture in the seat through which the plunger projects.

Compressor air or other operating fluid is introduced behind the plunger piston 72 by a conduit 82 thereby to move the plunger 68 to force the stud S resting upon the insert 55 into the cavity 52. The stud S is then conveyed through 40 the cavity 52 into the conduit 22 which is secured to the bottom of the body 32 by means of a flange 84 and thence to the welding gun 24. Air leading by the piston 72 is vented through a passageway 86 in the body 32.

As is shown in Figs. 12 through 14, the lower 50 bifurcated insert 55 can be replaced by a shoulder 55a of tungsten carbide and two oppositely disposed pointed pins which are threaded into apertures in the backplate 34 and cover plate 48 respectively. The studs are locked in position by 55 the nuts 64 to permit the tip portion to pass therebetween but to restrain the shank portion of the studs S. The bifurcated member is replaced by similarly arranged pins 69c and 69d.

The studs S are introduced into the passage 60 68 by means of an escapement, preferably pneumatically operated such as the escapement 26 which can be synchronized with the operation of the plunger 68. The escapement 26 comprises a body 90 wherein is provided an aperture such as the passageway 92 along into the top of which the studs S are introduced. The travel of the studs along the passageway 92 is normally blocked, as in Fig. 3, by a finger 94 which is reciprocatingly disposed in an aperture having an axis disposed perpendicularly to the axis of the passageway 92.

The finger 94 is biased in its passage-blocking position by a spring 96, one end of which seats 70 upon a piston 98 attached to one end of the fin-

ger. The opposite end of spring 98 seats in a recess in a head 100 which is attached to the side of the body 90 by the bolts 99. Arranged on either side of the centrally positioned finger 94 at a distance therefrom greater than the overall axial length of a stud S are two flanking fingers 102 and 103, respectively. With the exception of their axial length these fingers 102 and 103 are similar in construction, each having a tungsten carbide tip at one end and a skirted piston 104 attached to the other end thereof. Springs 107 are arranged circumjacent the fingers 102 and 103, respectively, between the correlated pistons 104 and the end of the cylinder apertures in the body 90 wherein the respective pistons 104 are disposed thereby to bias the fingers so that the ends thereof are normally clear of the passageway 92.

The finger 94 is moved out of the path of the studs S against the restoring force exerted by the spring 96 by compressed air or other working fluid introduced through a conduit 106 (Fig. 2) in the side of the body 90 into the cylinder aperture on the finger side of the piston 98. After the piston 98 has moved a sufficient distance to uncover ports 108, air is introduced behind the pistons 104 so that the corresponding fingers 102 and 103 are moved into the passageway 92.

The escapement 26 is mounted on the top of the orienting device 20, being secured thereto by a strap 110 which is bolted to the sides of the escapement and device by means of the bolts 112 so that the feed passageway 92 in the escapement is in alignment with the passageway 54 in the orienting device. This alignment is maintained by a bushing 114, the ends of which are pressed into the bodies 26 and 90, respectively. The aperture in the bushing 114 is tapered to eliminate any discontinuities at the junction of the passageways 54 and 92. The conduit 28 leading from the magazine 30 is aligned with the top of the passageway 92 by means of a flange 116.

The conduits 82 and 106 are connected to the supply of compressed air through a conventional two-way control valve (not shown), one position of which connects the conduits to the air supply, the other valve position bleeding the conduits to atmosphere. The control valve may be actuated either mechanically, pneumatically or electrically, depending upon the means of operation of the apparatus associated therewith, the actuating mechanism being arranged to complete one operating cycle of the valve during each cycle of the welding gun 24.

As described heretofore, the studs S are fed from the magazine 30 to the conduit 28 in random axial orientation. The studs S proceed along the conduit 28 under the force of gravity, aided, if necessary, by a stream of compressed air, thence through the passageway 92 until their forward progress is blocked by the finger 94. The connecting of the conduit 106 to the compressed air supply by the control, as described above, retracts the finger 94 so that the stack of studs S is permitted to travel further along the passageway 92. When the finger 94 has been retracted sufficiently so that the piston 98 uncovers the ports 108, the fingers 102 and 103 are moved into the passageway 92 so that the next to the bottom stud is forced against the passageway wall by the finger 102 thereby restraining further movement of the stack, the finger 103 simultaneously blocking the passageway to restrain the bottom stud which has dropped to the position shown in Fig. 4.

The subsequent venting of the conduit 106 to 75

atmosphere by the control valve permits the spring 96 to return the finger 94 so that it again blocks the passageway 92. The conjoint movement of the piston 98 bleeds the cylinders of the pistons 104 to atmosphere through the ports 108 and a vent 120 so that the springs 107 retract the fingers 102 and 103. The retraction of finger 102 releases the stack of studs so that it drops until again restrained by the finger 94. The simultaneous retraction of the finger 103 releases the bottom stud so that it drops through the passageway 54 in the orienting device 26 until the stud comes to rest in the recess in the insert 55.

Upon the operation of the control valve, air under pressure is also supplied behind the piston 72 by the conduit 82 so that the finger 68 is moved to force the stud resting upon the insert 55 from the preceding operation of the escapement 26 into the cavity 52. If the stud S is resting with the end of its shank portion upon the insert 55 (Fig. 6), the tines of the bifurcated lip portion 56 restrain such shank portion as the tip portion passes between the tines of the bifurcated end 60 so that the stud is turned end for end as it is moved by the plunger 68, the tip portion descending foremost, as is shown in Fig. 9. If the stud is resting upon its tip portion (Fig. 10), the movement of the plunger 68 forces the tip portion between the tines of the insert lip 56. The shank portion is restrained by the tines of the end 60 so that the stud again descends tip foremost, as is shown in Fig. 11.

It will be understood that the lips 56a, 56b of base 55 and the tines 60a, 60b of bifurcated end 60 (Figs. 6 to 11) perform the same function as the pin points 56c, 56d and the pin points 60c, 60d (Figs. 12 to 14), namely those of relatively movable diameter gauges which together constitute a selective ejector stop. The two gauges, by virtue of the effective distance of their jaws (the gaps 56a—56b, 60a—60b and 56c—56d, 60c—60d, respectively), discriminate between shank and tip diameters of the studs, whereas the stop defined by the gauge pair, as by virtue of the effective distance between the gauges, selectively ejects the studs as discriminated by the gauges so that both originally "tip up" studs and "tip down" studs enter conduit 52 in the proper "tip down" position.

It should be understood that the present disclosure is for the purpose of illustration only and that this invention includes all modifications and equivalents which fall within the scope of the appended claims.

We claim:

1. A device for orienting studs of the type having an extending tip portion of lesser diameter than its shank portion, comprising a stop for engaging one end of a stud, means for introducing a stud into said device so that a random end thereof comes to rest on said stop, a bifurcated member positioned adjacent either end of said stud as it rests upon the stop, the spaces between the tines of both bifurcated members being greater than the diameter of the tip portion and lesser than the diameter of the shank portion, and means for moving a stud from said stop to bring the shank portion thereof into contact with the tines of one of said bifurcated members and conjointly to cause the tip portion to pass between the tines of the other member thereby to release said stud from said device, tip portion foremost, irrespective of the orientation with which the stud was introduced into said device.
2. A device for orienting studs of the type hav-

ing an extending tip portion of lesser diameter than its shank portion, comprising a stop for engaging one end of a stud, means for introducing a stud into said device so that a random end thereof comes to rest on said stop, a bifurcated member positioned adjacent either end of said stud as it rests upon the stop, the spaces between the tines of both bifurcated members being greater than the diameter of the tip portion and lesser than the diameter of the shank portion, and a pneumatically operated plunger having a path of action intermediate the bifurcated members transverse the axis of a stud resting upon said stop for moving said stud from said stop to bring the shank portion thereof into contact with the tines of one of said bifurcated members and conjointly to cause the tip portion to pass between the tines of the other member thereby to release said stud from said device, tip portion foremost, irrespective of the orientation with which the stud was introduced into said device.

3. A device for orienting studs of the type having an extending tip portion of lesser diameter than its shank portion, comprising a first member having a recess, one wall of which recess is formed by a projecting bifurcated lip, the bottom of the recess forming a stop, means for guiding a stud introduced into said device so that a random end thereof rests upon the stop, a second member having a bifurcated portion arranged at a distance from the bottom of the recess substantially equal to the length of the shank portion of a stud so that said bifurcated portion is adjacent the opposite end of a stud resting upon the stop, the spaces between the tines of both the lip and bifurcated portion being greater than the diameter of the tip portion and lesser than the diameter of the shank portion, and means for moving a stud from said stop to bring the shank portion thereof into contact with the tines of one of said bifurcated members and conjointly to cause the tip portion to pass between the tines of the other member thereby to release said stud from said device, tip portion foremost, irrespective of the orientation with which the stud was introduced into said device.

4. A device for orienting studs of the type having an extending tip portion of lesser diameter than its shank portion, comprising a first member having a recess, one wall of which recess is formed by a projecting bifurcated lip, the bottom of the recess forming a stop, means including a passageway arranged so that a stud introduced into said device comes to rest with a random end resting upon the stop, a second member having a bifurcated portion arranged at a distance from the stop which is substantially equal to the length of the shank portion of a stud so that said bifurcated portion is adjacent the opposite end of a stud resting upon the stop, the spaces between the tines of both members being greater than the diameter of the tip portion and lesser than the diameter of the shank portion, and a pneumatically operated plunger having a path of action transverse the passageway for moving a stud from said stop to bring the shank portion thereof into contact with the tines of one of said bifurcated members and conjointly to cause the tip portion to pass between the tines of the other member thereby to release said stud from said device, tip portion foremost, irrespective of the orientation with which the stud was introduced into said device.

5. A device for orienting studs of the type hav-

ing an extending tip portion of lesser diameter than its shank portion, comprising a body having a cavity wherein a stud is fed, the wall of said cavity having a shoulder with a bifurcated lip forming a stop wherein a random end of each stud comes to rest as it is fed into the device, a member having a bifurcated end arranged at a distance from the stop which is substantially equal to the length of the shank portion of a stud so that said bifurcated portion is adjacent the opposite end of a stud resting upon the stop, the spaces between the tines of both the bifurcated lip and the bifurcated member being greater than the diameter of the tip portion and lesser than the diameter of the shank portion, and means for moving a stud from said stop to bring the shank portion thereof into contact with the tines of one of said bifurcated members and conjointly to cause the tip portion to pass between the tines of the other member thereby to release said stud from said device, tip portion foremost, irrespective of the orientation with which the stud was introduced into said device.

6. A device for orienting studs of the type having an extending tip portion of lesser diameter than its shank portion, comprising a stop for engaging one end of a stud, means for introducing a stud into said device so that a random end thereof comes to rest on said stop, two pairs of cooperative fingers, one of which pairs is located adjacent said stop, the other pair being positioned at a distance from the stop which is substantially equal to the length of the shank portion of the stud, the spaces between the fingers of both pairs being greater than the diameter of the tip portion and lesser than the diameter of the shank portion, and means for moving a stud from said stop to bring the shank portion thereof into contact with one pair of said fingers and conjointly to cause the tip portion to pass between the other pair of said fingers thereby to release said stud from said device, tip portion foremost, irrespective of the orientation with which the stud was introduced into said device.

7. A device for orienting studs of the type having an extending tip portion of lesser diameter than its shank portion, comprising a stop for engaging one end of a stud, means for introducing a stud into said device so that a random end thereof comes to rest on said stop, two pairs of cooperating fingers one of which pairs is located adjacent said stop, the second pair being positioned at a distance from the stop which is being substantially equal to the length of the shank portion of a stud so that said second pair is adjacent the opposite end of said stud, the spaces between the fingers of both pairs being greater than the diameter of the tip portion and lesser than the diameter of the shank portion, and a power operated plunger having a path of action intermediate the pairs of fingers transverse the axis of a stud resting upon the stop for moving said stud from said stop to bring the shank portion thereof into contact with one pair of said fingers and conjointly to cause the tip portion to pass between the other pair of said fingers thereby to release said stud from said device, tip portion foremost, irrespective of the orientation with which the stud was introduced into said device.

8. A device for orienting studs of the type having an extending tip portion of lesser diameter than its shank portion, comprising a body including a passageway having a shoulder forming a stop arranged so that a stud inserted in the passageway comes to rest with a random end resting upon

the stop, a first pair of cooperating fingers located adjacent said stop, a second pair of cooperating fingers arranged at a distance from said stop substantially equal to the shank portion of a stud so that said second pair is adjacent the opposite end of a stud resting upon said stop, the spaces between the fingers of both pairs being greater than the diameter of the tip portion and lesser than the diameter of the shank portion, and a power operated plunger having a path of action transverse the passageway for moving a stud from said stop to bring the shank portion thereof into contact with one pair of said fingers and conjointly to cause the tip portion to pass the other pair of said fingers thereby to release said stud from said device tip portion foremost irrespective of the orientation with which the stud was introduced into said device.

9. A device for orienting studs of the type having an extended tip portion of lesser diameter than its shank portion, comprising a body having a cavity wherein the studs are successively fed, the wall of the cavity having a shoulder forming a stop whereon a random end of a stud comes to rest as it is fed into the device, a pair of oppositely disposed pins arranged adjacent said shoulder, a second pair of oppositely disposed pins arranged with respect to the shoulder at a distance

substantially equal to the length of the shank portion of a stud so that said second pair is adjacent the opposite end of a stud resting upon said stop, the spaces between the pins of both pairs being greater than the diameter of the tip portion and lesser than the diameter of the shank portion, and means for moving a stud from said stop to bring the shank portion thereof into contact with one pair of said pins and conjointly to cause the tip portion to pass between the other pair of said pins thereby to release said stud from said device, tip portion foremost, irrespective of the orientation with which the stud was introduced into said device.
